UNITED STATES PATENT OFFICE

EDWARD A. WETZEL, OF ROYAL OAK, MICHIGAN, ASSIGNOR TO HALE & KILBURN CO.,
OF PHILADELPHIA, PENNSYLVANIA, A CORPORATION OF DELAWARE

AUTOMOBILE DOOR

Application filed April 15, 1925. Serial No. 23,170.

This invention relates to automobile doors, and more particularly relates to doors of all steel construction.

One of the objects of my invention is to provide a door, of extreme simplicity of construction, having very few parts. Another object of my invention is to provide a door which may be assembled quickly and easily. A further object of my invention is to provide a door which has great strength and rigidity and affords increased clear vision, and at the same time is attractive in appearance. Another object of my invention is to eliminate squeaking and also to eliminate drumming vibration carrying from one panel to another. Further objects of my invention are also directed to reduction in cost and economy in the construction and assembly of the door.

Other objects of my invention will be in part obvious and in part pointed out hereinafter.

In accordance with my invention, I form the component units which make up the door in such shapes that the door will give extended clear vision, that only a few parts are required for the complete door, that it is not necessary to use any heavy gauge metal, and that the frame can be assembled complete in one jig and the panels applied complete in another operation. Along each side edge of the door I form a dovetail groove, which serves three distinct purposes. One purpose is to allow for the insertion of a rubber tube which will act as a wind break when the door is closed. A second purpose is to provide space for attaching the door hinges. A third purpose is to obtain reenforcement and added rigidity to the pillar along which the dovetail is formed. The invention also contemplates the provision of a window regulator mounting which permits ready access to the regulator for replacement and repair.

In order that a clearer understanding of my invention may be had, attention is hereby directed to the accompanying drawings, forming a part of this application and illustrating one possible embodiment of my invention.

Referring to the drawings, Fig. 1 is a front view of an assembled door embodying my

invention, certain of the parts being shown in dotted lines to bring out certain features of the construction; and Figs. 2, 3, 4, 5, 6 and 7 are each sectional views of portions of the construction, and are taken respectively on the lines 2—2, 3—3, 4—4, 5—5, 6—6 and 7—7 of Fig. 1, Figs. 6 and 7 being enlarged and including hinge mounting and a portion of the door jamb.

Similar reference characters refer to similar parts throughout the several views of the drawings.

Referring to the drawings, the door includes a hinge pillar 1, which is made up of a single piece of light gauge steel running the full height of the door. This pillar is formed with a flange 2 parallel with the outside of the door and to which is attached the outside lower panel 3 and the outside upper panel 4, which panels may be clinched around the flange 2 wherever necessary, and may also be spot welded thereto. Pillar 1 is also pre-formed with a dovetail groove 5, which runs the full length of the pillar. A preformed flange 6 of this pillar forms its inside face, and above the belt rail this flange is curled over, as at 7, to provide a finish moulding. Below the belt rail a flange 8 is broken off flange 6 to reenforce the pillar between the regulator mounting panel 9 and the bottom frame 10. As this pillar section is formed, it can be rolled in one operation instead of several press operations.

The lock pillar 11 is formed in conventional section, with a flange 12 parallel with the outside of the door and about which the panels 3 and 4 are clinched. Above the belt rail is a flange 13 curved, as at 14, to provide a finish moulding above the belt rail, and below the belt rail is a flange 15, from which a flange 16 is broken off between the regulator mounting 9 and the bottom frame 10.

The headrail frame 17 is made up of a Z-shaped stamping, which is welded to the pillars 1 and 11. This rail has a flange 18 at upper edge, about which the outside panel is clinched, as on the sides and bottom of the door, making a very strong and rigid construction.

The bottom frame 10 has an inside face, 100

which has a flange 19 along its top edge, which, in turn, is flanged, as at 20, creating a channel formation and at the same time providing a bearing surface against panel 3. 5 Preferably a strip of felt 21, or similar material, is inserted between this flange and the door panel 3 to prevent squeaking and to prevent drumming from being transferred from one part to another. Along the lower 10 edge of frame 10 is a forwardly extending flange 22, which is flanged downwardly, as at 23, along its edge, and around this flange 23 the bottom of the outside panel 3 is clinched. Frame 10 has end flanges 24 15 which abut and are welded to the pillars 1 and 11.

The regulator mounting may be made in three pieces, including a plate or panel strip 9, a top panel strip 25, and a bottom panel 20 strip 26. Panel strips 25 and 26 have flanges 27 and 28 along their edges welded to the panel strip 9, which, in turn, has flanges 29 and 30 welded to the door pillars 1 and 11. A box section 31 is also mounted on the panel 25 strip 9, and in this the window regulator (not shown) may be carried. Preferably a cutout or perforation is provided, as at 32, to allow the insertion of a socket wrench, or other tool, for assembling the regulator, and providing 30 easy access thereto for replacement and repair.

Where the upper and lower outside door panels meet, the upper panel is preferably beaded, as at 33, and overlaps the lower panel, and along this line the panels are preferably welded together.

The upper panel 4 is preferably formed of one piece of metal clinched over the pillars on its sides and clinched over the headrail frame along its top edge, as stated. On the 40 sides of the window opening this panel is formed to shape a window run in conjunction with the flanges 7 and 14 of the pillars 1 and 11. This panel may be pre-formed with a flange 46, which seats behind the bottom wall 45 of the dovetail groove in post 1 and against a part of the outer wall of panel 11, and to which this flange may be welded, whereby a 50 strong and rigid construction in the least possible amount of space is secured, with a complete assembly, and affording extended clear vision.

A finish strip or moulding 34 is preferably added along the inside top edge of the door, 55 this strip having a curled flange 35, similar to side formations 7 and 14. Preferably a space is left between this moulding and the head-rail frame to allow for the assembly of the window glass, since this glass is adapted 60 to be let down into the window run through the top of the door.

Along the hinge pillar a rubber tube or cushion 36 is anchored within the dovetail groove, so as to protrude from the pillar and 65 to be compressed by engagement with the door

jamb 37 when the door is closed, thus constituting a wind-break. As the construction of this door does not require trimming material above the belt rail, due to the small sections exposed and the moulding shape, it would be 70 inconvenient and unsightly to have a wind-break to cover the opening between the door and the body pillars on the inside, as is the usual practice. This, however, has been avoided in the manner above described.

The dovetail formation along the hinge side of the door also serves as space for attaching the door hinges 38, as shown in Fig. 7. The hinge bar 39 seats behind the outer face of the pillar 1 and extends across the dovetail groove. A filler block 40, preferably metal, is placed in the dovetail groove behind the hinge bar, and the bar is secured in place by means of screws 41. At this point the wind cord 36 may be cut away. The complementary hinge bar 42 may be attached to the door jamb in the usual way, as by screws 43.

For strengthening and stiffening purposes, the panel strip 9 of the regulator mounting may be provided with horizontal beads 44 and 80 with zig-zag beads 45.

To eliminate squeaking and drumming vibrations carrying from one panel to another, soft material, such as felt, may be interposed at the joints between the sheet metal parts, for instance, wherever a panel is clinched over 95 the flanges of the frame member.

From the above it will be readily apparent that the assembly comprises a minimum number of parts and at the same time has the required weight, strength, rigidity, and also has an exceptionally extensive vision. It will also be noted that only light gauge sheet metal is required and that the construction is conducive to economies in manufacturing expenses.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:

1. In a door of the character described, in combination, a pillar strip having an outward flange along one edge and an inward flange along its other edge, and a panel strip secured at one edge to the outward flange of the pillar strip and having at its other edge a flange seating against and secured to the body of the pillar strip, said panel strip having an inwardly extending portion forming a window runway in conjunction with the inward pillar strip flange.

2. In a door of the character described, in combination, a pillar strip having along one edge an inward flange forming one side wall

of a window runway, a panel strip having an inwardly extending portion forming the opposite side wall of the window runway, and having an edge flange seating on and secured to the body of the pillar strip intermediate 5 said runway walls, and the other edges of the pillar strip and panel strip being secured together.

3. In a door of the character described, in combination, a pillar strip having along one edge an inward flange said flange having a curled over extremity forming one side wall of a window runway, a panel strip having an inwardly extending portion forming the opposite side wall of the window runway, and having an edge flange seating on and secured to the body of the pillar strip, the other edge of the panel strip being flanged over the other edge of the pillar strip.

4. In a door of the character described, in combination, a pillar strip having along one edge an inward flange said flange having a curled over extremity forming one side wall of a window runway, a panel strip having an inwardly extending portion forming the opposite side wall of the window runway, and having an edge flange seating on and secured to the body of the pillar strip intermediate said runway walls, the pillar strip 30 having an outward flange along its other edge, and the other edge of the panel strip being clinched over this outward flange.

5. In a door of the character described, a sheet metal post pre-formed with a dovetail recess along its face and with an outwardly extending flange along one edge, and a panel member attached along one edge to said outwardly extending flange and having another portion secured to a wall of said dovetail 40 recess.

6. In a door of the character described, a sheet metal post pre-formed with a dovetail recess along its face and with an outwardly extending flange along one edge and with an inwardly extending flange along the other edge, a portion of said flange being curved over to form a finish moulding, and a panel member attached along one edge to said outwardly extending flange and having another portion secured to a wall of said dovetail 45 recess, said panel member cooperating with said finish moulding flange to form a runway for window glass.

7. In a door of the character described, a sheet metal post pre-formed with a dovetail recess along its face and with an outwardly extending flange along one edge, a panel member attached along one edge to said flange and having another portion secured to the 55 post at the dovetail recess, and a strip of flexible material disposed in said recess and protruding outwardly of the face of the post.

8. In a door of the character described, a sheet metal post pre-formed with a dovetail recess along its face, and a hinge having a

bar disposed against and secured to the rear side of the face of the post, said bar penetrating said dovetail recess.

9. A window rail comprising a principal section of angle form, and a reinforcing member therefor comprising a member of channel section secured to one member of said angle mouth down and having its side wall most closely adjacent to the other branch of said angle co-operating therewith to form a 70 glass run.

10. In a door of the character described, in combination, a sheet metal pillar strip having a portion flanged to form part of a window runway, and a panel strip flanged to 80 form the complementary portion of the window runway and secured to the pillar strip at the base of said runway, said pillar strip having an outwardly-extending flange along one edge and said panel strip having an edge 85 clinched over said flange.

11. A window rail for doors of closed vehicle bodies comprising a main body member having a transversely extending web portion arranged substantially in the plane of the 90 jamb face of the door and a panel stamping of hollow form open on a side secured mouth down upon the inner face of said web portion and having an inwardly facing wall forming a side of a glass run.

12. A metal window rail for doors of closed vehicle bodies comprising a main body member having a transversely extending web portion arranged substantially in the plane of the jamb face of the door and a lateral flange along the inner edge of said web portion, and a panel stamping of hollow form open on a side secured mouth down upon the inner face of said web portion and having a wall adjacent the lateral flange of said main member 100 cooperating therewith to form a glass run.

13. In a door for closed vehicle bodies, in combination, a metal frame member having a portion flanged to form part of a glass run, and a sheet metal panel stamping flanged to form the complementary portion of the glass run and secured to the frame member at the base of the glass run, said frame member having a flange along one edge and the panel stamping having an edge secured to said 110 flange.

14. In a door, the combination with a pillar having oppositely projecting flanges, of a panel secured to one of said flanges having a window opening, and a flange projecting laterally from one edge of the opening having a substantially L-shaped extension forming the base and one side of a channel-shaped runway and cooperating with the other of said pillar flanges to form the completed channel-shaped runway for a glass panel.

This specification signed this 7th day of April, 1925.
